UNITED STATES PATENT OFFICE.

ALBERT C. LINK, OF DETROIT, MICHIGAN, ASSIGNOR TO THE L. A. YOUNG COMPANY, OF DETROIT, MICHIGAN.

GOLF CLUB.

Application filed April 5, 1928. Serial No. 287,721.

The main objects of this invention are:

First, to provide a golf club in which the weight is so disposed as to act as a balancing feature, centering the weight in approximately the center of the striking face as the blow is delivered.

Second, to provide a golf club in which the weight is so disposed that the impact does not tend to dislocate the weight.

10 Objects relating to details and economies of my invention will appear from the description to follow. The invention is defined and pointed out in the claims.

A structure which is a preferred embodiment of my invention is illustrated in the accompanying drawing, forming a part of this application, in which:

Fig. 1 is a rear perspective view of my improved golf club, the shank being broken away.

Fig. 2 is a sectional view from front to rear through the vertical center of the striking face and vertical center of the weight taken on line 2—2 of Figs. 1, 4 and 5.

25 Fig. 3 is a detail section on line 3—3 of Figs. 1 and 5.

Fig. 4 is a detail horizontal section on line 4—4 of Figs. 1 and 5.

Fig. 5 is an inside view of the weight.

30 In the drawing similar reference characters refer to similar parts throughout the several views.

Referring to the drawing, the head 1 is preferably formed of wood and is provided 35 with a striking face designated generally by the numeral 2, this striking face illustrated being that illustrated in my Patent No. 1,659,272 dated February 14, 1928.

The rear edge of the head has a vertical 40 V-shaped recess 3 therein centering in approximately the vertical plane of the center of the striking face. At each side of this recess, the rear edge of the head is formed with two segmentally curved surfaces 4 and 45 5 centering approximately in the center of the head and disposed at an angle, the angle being in approximately the horizontal center of the rear portion of the head.

The weight comprises a central vertical 50 V-shaped body portion 6 conformed to fit in the recess 3 and segmental wing portions 7 and 8 disposed at an angle to each other and conformed on their inner faces to fit the surfaces 4 and 5.

55 The weight is secured in place by the

screws 9 arranged through holes 10 in the wing portions adjacent the edges of the body portion. The outer surface of the weight is complementary, that is, it is a curve complementing the rear edge of the head. 60

With the head thus conformed and the weight thus shaped and arranged, the impact of the weight tends to securely seat it and at the same time the impact is centered in approximately the center of the striking 65 face of the head. Further, the impact does not tend to shift the weight or its fastenings but rather to hold it to its seat.

I have not attempted to illustrate or describe my improvements in certain modifications or adaptations which might be desirable as it is believed this disclosure will enable those skilled in the art to embody or adapt my improvements as may be desired. 70

Having thus described my invention, what 75 I claim as new and desire to secure by Letters Patent, is:

1. In a golf club, the combination of a head member having a vertical V-shaped recess in its rear edge centering in approximately the vertical plane of the center of the striking face, the rear edge of said head at each side of said recess being conformed to provide two curved surfaces centering at approximately the center of the striking 80 face and meeting at an angle in approximately the horizontal center of the head, and an integral weight comprising a central vertical V-shaped body portion fitting in said vertical recess and segmental wing 85 portions disposed at an angle to each other and curved on their inner faces to correspond to and clamped upon said curved surfaces of said head, said body and wing portions having a continuous outer curved 90 surface complementing the rear edge of the head at each end thereof. 95

2. In a golf club, the combination of a head member having a vertical V-shaped recess in its rear edge centering in approximately the vertical plane of the center of the striking face, the rear edge of said head at each side of said recess being conformed to provide two curved surfaces centering at approximately the center of the striking 100 face and meeting at an angle in approximately the horizontal center of the head, and an integral weight comprising a central vertical V-shaped body portion fitting in said vertical recess and segmental wing por- 105

110

tions disposed at an angle to each other and curved on their inner faces to correspond to and clamped upon said curved surfaces of said head.

5. 3. In a golf club, the combination of a head member having a vertical V-shaped recess in its rear edge centering in approximately the vertical plane of the center of the striking face, the rear edge of said head
10 at each side of said recess being conformed to provide two surfaces meeting at an angle in approximately the horizontal center of the head, and an integral weight comprising a central vertical V-shaped body portion fitting in said vertical recess and segmental wing portions disposed at an angle to each other and conformed on their inner faces to correspond to and clamped upon said surfaces of said head, said body and wing portions having a continuous outer curved surface complementing the edge of the head.
- 15 4. In a golf club, the combination of a head member having a vertical V-shaped recess in its rear edge centering in approximately the vertical plane of the center of the striking face, the rear edge of said head
20
25

at each side of said recess being conformed to provide two surfaces meeting at an angle in approximately the horizontal center of the head, and an integral weight comprising a central vertical V-shaped body portion fitting in said vertical recess and segmental wing portions disposed at an angle to each other and conformed on their inner faces to correspond to and clamped upon 30
35 said surfaces of said head.

5. In a golf club, the combination of a head member having a vertical recess of V-cross section centering in the center of the striking face and oppositely inclined 40 surfaces at each side of said recess centering at approximately the center of the striking face and meeting in approximately the horizontal center of the head, and an integral weight comprising a V-shaped body 45 portion fitting in said recess and wing-like members conforming to said surfaces at the sides thereof and clamped thereon.

In witness whereof I have hereunto set my hand.

ALBERT C. LINK.
